NO. 13,074

July 25, 1882

UNITED STATES PATENT OFFICE.

JAMES M. BRYCE, OF BEVERLY, NEW JERSEY.

DESIGN FOR A PRINTED FABRIC.

SPECIFICATION forming part of Design No. 13,074, dated July 25, 1882.

Application filed May 18, 1882. Term of patent 3½ years.

To all whom it may concern:

Be it known that I, JAMES M. BRYCE, of Beverly, in the county of Burlington, and State of New Jersey, have invented a new and original Design for Printed Fabrics; and I do hereby declare that the following specification, taken in connection with the accompanying illustration, forming a part of the same, is a full, clear, and exact description thereof.

My design relates particularly to printed fabrics known as "calicoes," although it is equally applicable to silks, woolens, and other fabrics, either printed or woven.

It consists in the representation of birds in flight and stalks of grain, as will hereinafter appear.

Referring to the illustration, A A' represent

different views of birds in flight, and B B' spears or stalks of grain arranged irregularly on the ground of the fabric. The birds and stalks of grain are repeated on the surface of the fabric to form the pattern.

The fabric may be produced in any preferred variety or combination of colors for giving to the design a desirable effect.

What I claim, and desire to secure by Letters Patent, is—

The design for printed and other fabrics, consisting of birds in flight and stalks of grain, substantially as described and shown.

JAMES M. BRYCE.
